UNITED STATES PATENT OFFICE.

WILLIS S. FARNSWORTH, OF SAN FRANCISCO, CALIFORNIA, ASSIGNOR TO COIN CONTROLLED LOCK CO., OF SAN FRANCISCO, CALIFORNIA, A CORPORATION OF CALIFORNIA.

COIN-CONTROLLED LOCK.

1,093,175.

Specification of Letters Patent. Patented Apr. 14, 1914.

Application filed May 14, 1912. Serial No. 697,142.

To all whom it may concern:

Be it known that I, WILLIS S. FARNSWORTH, a citizen of the United States, residing at the city and in the county of San Francisco and State of California, have invented new and useful Improvements in Coin-Controlled Locks, of which the following is a specification.

This invention relates to a coin controlled lock, and particularly pertains to mechanism for controlling the operation of the lock by means of coins, slugs or other tokens.

It is the object of this invention to provide a lock which is so constructed and arranged that it can be operated only by the depositing of a proper coin or token.

A further object is to provide a coin controlled device which is adapted to be applied to the ordinary cylinder locks now generally in use, with but slight alteration of the lock structure.

Another object is to provide a coin controlled lock in which the use of dogs, trip levers, pawls, or other tripping and releasing mechanisms are dispensed with, thereby producing a coin-controlled lock, which is simple in construction and efficient and reliable in operation.

Still another object is to provide a coin controlled lock which is so arranged that the coin employed in operating the lock will be exposed when the bolt of the lock is in its locked position; and which is not liable to become choked by the insertion of additional coins, and to provide means for automatically partially discharging the key when the bolt is thrown and prevent the bolt being accidentally retracted.

Other objects will appear in the following specifications.

The invention consists of the parts and the combination and construction of parts as hereinafter more fully described and claimed, having reference to the accompanying drawings, in which—

Figure 1 is a rear view of the lock with casing removed, showing the bolt in its retracted position and locked against movement. Fig. 2 is a similar view showing the bolt in its advanced position. Fig. 3 is a detail showing the bolt as retracted and showing the coin in the position assumed

following its deposit. Fig. 4 is a similar view showing the bolt in its advanced position. Fig. 5 is a horizontal section on the line X—X, Fig. 3. Fig. 6 is a detail vertical section of a cylinder lock. Fig. 7 is a detail vertical section on the line Y—Y, Fig. 3.

In the drawings, A represents a face plate or escutcheon which is designed to be placed on the outer face of the door or casing to which the lock is to be applied; this escutcheon plate being formed with a slot 2 for the reception of coins, and which slot opens to a coin chute 3 mounted on the back of the escutcheon A.

A base plate 4, on which the lock mechanism is supported, is mounted on the back of the escutcheon A and is provided with an outwardly projecting flange 5 which is formed with a vertical slot 5' arranged to receive the forward end of a bolt 6. The bolt 6 parallels the plate 4 and is spaced a short distance therefrom, as shown in Fig. 5, and is supported and guided at its rear end upon a bracket 7 formed on the base plate 4 and projecting beneath the lower edge of the bolt; the bracket 7 being slotted to extend on each side of the bolt, as shown in Fig. 7. A pin 8 is positioned on the bolt 6 to strike the bracket 7 on its forward face to limit the rearward movement of the bolt.

Mounted on the base plate 4, above the bolt 6, is an ordinary cylinder lock of any suitable type, which is here shown as consisting of a barrel B mounted in a cylindrical casing C and having the usual loose pins or tumblers D and E which are actuated by the insertion of a key F in the keyhole G extending longitudinally through the barrel B. A bit or projecting pin 9 is suitably attached to the inner end of the barrel B adjacent to the base plate 4 and is normally positioned to extend at an angle into a notch or slot 10 formed in the upper edge of the bolt 6. Mounted on the bolt 6 and extending toward the base plate 4 is a pin 11 which is positioned on the bolt adjacent to its lower edge. Mounted on the base plate 4 is a pin 12, which extends across the space between the base plate 4 and the inner face of the bolt 6 and terminates adjacent to the latter, as shown in Fig. 5; the

pins 11 and 12 being diagonally spaced apart a distance slightly greater than the diameter of the coin to be employed.

As a means for preventing the bolt 6 being advanced by the rotation of the lock barrel B, a hump 13 is formed on the lower edge of the bolt rearward of and adjacent to the bracket 7 in such position as to engage the bracket 7 when the bit 9 is brought to bear against the forward edge of the slot 10, as indicated in dotted lines in Fig. 1. The pressure of the bit 9 against the forward edge of the slot 10 causes the hump 13 to tend to ride over the supporting edge of the bracket 7, which action, however, is normally prevented by means of a plate spring 14 mounted on the lower edge of the bolt 6, the outer end of which abuts against a stop 15 on the plate 4, as shown in Figs. 1 and 3, thus preventing the forward movement of the bolt. The rear end of the bolt carrying the hump 13 is normally retained in its lowermost position by means of a plate spring 16 on the upper edge of the bolt.

25 The slot 10 is formed in the bolt 6 in such a position and of such width as to limit the movement of the bit 9 and thereby hold the barrel B in such a position as to dispose the pins E out of alinement with the loose pins D mounted in the casing C, as shown in Fig. 1; the pins E bearing against the walls inside of the cylinder C. When the parts are in this position, the key F is blocked against removal, as is well known in locks of the Yale type in which the key can only be withdrawn when the keyhole and key stand in a certain position, usually vertical, to dispose the pins E in the barrel B in alinement with the pins D in the cylinder C and allow the pins E to move up into the recesses holding the pins D as they ride over the serrations on the key F when the latter is inserted or withdrawn.

45 From the foregoing it will be seen that when the bolt 6 is in the retracted position shown in Fig. 1, it cannot be advanced, nor can the barrel B of the lock be turned sufficiently far to admit of the withdrawal 50 of the key F therein; the hump 13 acting in conjunction with the spring 14 and shoulder 15 to block the bolt 6 against forward movement, which blocking of the bolt causes the forward edge of the slot 55 10 to limit the movement of the bit 9 on the barrel B.

The coin chute 3 leads to and terminates above the space between the bolt 6 and base plate 4, as shown in Figs. 1 and 2, in such a manner that when a coin is discharged therefrom the coin will fall between the pins 11-12 and be supported upon the pins 11-12 and a finger 17 on the spring 14 when the bolt 6 is in its retracted position, as shown in dotted lines in Fig. 3.

In the operation of this invention, a coin 18 of the proper value, or a suitable token, is inserted in the slot 2, from which it passes down the chute 3 and is delivered behind the bolt 6 only to come to rest on the respectively movable and fixed pins 11 and 12 and the finger 17, as just described; the pins 11 and 12 being spaced apart according to the diameter of the coin to be used. The key F is then operated to rotate the barrel B to turn the bit 9 in the direction of the arrow in Fig. 3 and thereby advance the bolt 6 a short distance. The pin 11 will strike the edge of the coin 18, at a point above its middle on the initial forward movement of the bolt 6, and thus cause the coin to bear against the fixed pin 12 which acts to deflect the coin 18 in a downward direction, which causes the coin to bear upon the finger 17 on the spring 14 and thereby throws the outer end of the spring 14 out of engagement with the shoulder 15. The bolt 6 is now moved to its advanced position and the coin 18 is released from the pins 11—12 and rests upon the finger 17 and against the rear face of the flange 5, as shown in dotted lines in Fig. 4, in which position it remains as long as the bolt is advanced; the coin being exposed to view through a perforation 19 formed in the plates A and 4. The key F may now be removed from the barrel B as the pins D and E will be in alignment. Should a second coin be deposited in the chute 3 either before or after the advancing of the bolt 6, it will strike the coin 18 and will pass behind the bolt 6 rearward of the pin 11 and the finger 17, and will fall into any desired receptacle below the lock. When the bolt is retracted, which is done by re-inserting the key F in the barrel B and turning the latter in the direction of the arrow in Fig. 4 to cause the bit 9 to engage the rear edge of the slot 10, the finger 17 will be withdrawn from beneath the coin 18 and the latter will be allowed to drop into any suitable receptacle, not shown. The movement of the bolt 6 is retarded in either direction by means of the plate springs 14 and 16 on the bolt, which bear against rigid portions of the lock in such a manner as to normally retain the bolt in its lowermost position and at the same time prevent too easy movement thereof.

Means are provided for partially ejecting the key F from the barrel B when the bolt 6 has been advanced, which means is here shown as consisting of a plate spring 20 mounted to bear against the inner end of the barrel B, as shown in Figs. 5 and 6. The key F is of such length that when it is inserted in the barrel B it will project a short distance beyond the inner end of the latter and contact the spring 20; the spring 20 thus offering a resistance to the insertion of 130

the key in the lock so that any possibility of the bolt being accidentally retracted will be obviated.

Having thus described my invention what I claim and desire to secure by Letters Patent is—

1. In a lock, the combination with a bolt, a key operated bit engaging the bolt, a plate spring on the bolt, a rigid shoulder engaged by the spring, means on the spring for supporting a coin, and means engageable with the coin controlled by the bit operating through the coin to throw the spring out of engagement with the shoulder.
2. In a lock, the combination with a bolt, a key operated bit engaging the bolt, a plate spring on the bolt, a rigid shoulder engaged by the spring, means on the spring for supporting a coin, and means engageable with the coin controlled by the bit operating through the coin to throw the spring out

of engagement with the shoulder, comprising a pin on the bolt and a fixed, stationary pin spaced therefrom.

3. In a lock, the combination with a bolt, a key operated bit engaging the bolt, a plate spring on the bolt, a rigid shoulder engaged by the spring, means on the spring for supporting a coin, means engageable with the coin controlled by the bit operating through the coin to throw the spring out of engagement with the shoulder, comprising a pin on the bolt and a fixed, stationary pin spaced therefrom, and means for delivering a coin between said pins to the spring.

In testimony whereof I have hereunto set my hand in the presence of two subscribing witnesses.

WILLIS S. FARNSWORTH.
